CLAIM

The ornamental design for a pet towel, as shown and described.

DESCRIPTION

FIG. 1 is a front perspective view of a pet towel showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines representing the closure fastener in FIGS. 1 through 3 have been provided for the purpose of illustrating portions of the claimed pet towel that form no part of the claimed design.

The dashed lines in FIG. 3 are understood to represent stitching.

The cross-hatched pattern in the views is understood to be continuous throughout the surfaces to which it is applied.
